U.S. Cl. D8—109

FIG. 1

FIG. 2

FIG. 3

FIG. 4

FIG. 5

FIG. 1 is a front perspective view of a paddle handle recessed lock embodying my new design;

FIG. 2 is a top plan view of the paddle lock;

FIG. 3 is a rear elevational view of the paddle lock;

FIG. 4 is an end view of the paddle lock looking into the left-hand end as viewed in FIG. 3; and

FIG. 5 is an end view of the paddle lock looking into the right-hand end as viewed in FIG. 3.

The broken line showing the lock bolt in FIGS. 1, 2, 3 and 5, the lock bolt housing in FIGS. 2, 3, 4 and 5, and the door and door frame in FIG. 1 are for illustrative purpose only.

The characteristic feature of the design is the stepped recess area adjacent to the handle portion.

I claim:

An ornamental design for a paddle handle recessed lock, substantially as shown and described.
